US00D991877S

(12) **United States Design Patent** (10) **Patent No.:** **US D991,877 S**
(45) **Date of Patent:** **** Jul. 11, 2023**

(54) **BATTERY**

(71) Applicant: **JUHEYUAN SCIENCE & TECHNOLOGY CO., LTD.**, Shenzhen (CN)
(72) Inventor: **Kewen Cheng**, Shenzhen (CN)
(73) Assignee: **JUHEYUAN SCIENCE & TECHNOLOGY CO., LTD.**, Shenzhen (CN)

(**) Term: **15 Years**

(21) Appl. No.: **29/776,202**

(22) Filed: **Mar. 29, 2021**

(30) **Foreign Application Priority Data**

Nov. 12, 2020 (CN) 202030685430.8
